[57] CLAIM

The ornamental design for a heated carrying case for medical IV bags, as shown and described.

DESCRIPTION

FIG. 1 is a front elevational view of a heated carrying case for IV bags showing our new design;

FIG. 2 is a top plan view thereof;

FIG. 3 is an elevation view thereof; the opposite side being of the same configuration;

FIG. 4 is a back elevation view thereof;

FIG. 5 is a bottom plan view thereof with bottom flaps on the case in closed position; and,

FIG. 6 is bottom plan view thereof with the bottom flaps of the case in open position.

FIG. 2

FIG. 1

FIG. 3

FIG. 5

FIG. 4

FIG. 6
